US0D1034567S

(12) **United States Design Patent** (10) **Patent No.:** **US D1,034,567 S**
(45) **Date of Patent:** **** Jul. 9, 2024**

(54) **PHONE CASE**

(71) Applicant: **Dongguan Lexin Photoelectric Technology Co., LTD.**, Dongguan (CN)

(72) Inventor: **Huisheng Zhu**, Dongguan (CN)

(73) Assignee: **Dongguan Lexin Photoelectric Technology Co., LTD.**, Dongguan (CN)

(**) Term: **15 Years**

(21) Appl. No.: **29/929,669**

(22) Filed: **Feb. 23, 2024**

(30) **Foreign Application Priority Data**

Aug. 25, 2023 (CN) 202330549646.5

(51) **LOC (14) Cl.** **14-03**

(52) **U.S. Cl.**

USPC **D14/250**

(58) **Field of Classification Search**

USPC D14/250, 253, 251, 426, 440

CPC H04M 1/04; H04M 1/0202; H04M 1/0283

See application file for complete search history.

(57) **CLAIM**

The ornamental design for a phone case, as shown and described.

DESCRIPTION

FIG. 1 is a front perspective view of a phone case, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the phone case, which form no part of the claimed design.

1 Claim, 8 Drawing Sheets
